William Mouat

BY J. S. Thomas

ATTORNEY

UNITED STATES PATENT OFFICE.

WILLIAM MOUAT, OF DETROIT, MICHIGAN.

FLUSH-VALVE.

1,320,565.

Specification of Letters Patent.

Patented Nov. 4, 1919.

Application filed February 6, 1919. Serial No. 275,341.

To all whom it may concern:

Be it known that I, WILLIAM MOUAT, citizen of the United States, residing at Detroit, county of Wayne, State of Michigan, have invented a certain new and useful Improvement in Flush-Valves, and declare the following to be a full, clear, and exact description of the same, such as will enable others skilled in the art to which it pertains to make and use the same, reference being had to the accompanying drawings, which form a part of this specification.

My invention relates to flush valves, shown in the accompanying drawings and more particularly described in the following specification and claims.

It is well known that the usual rubber ball valve, commonly employed in flushing tanks, has a rather limited period of usefulness due to the fact that it soon loses its shape and as a result will not seat properly, whereupon it must be discarded for another valve.

Valves formed of buoyant material, such as cork, have been used, but are objectionable due to the fact that they are not sufficiently resilient to seat properly.

It is therefore the object of this invention to provide a valve which is not open either to the objections common to the hollow ball valve, or to valves constructed of buoyant material.

A further object of the invention is to provide a device which may be applied to valves now in use in order that a proper seating of the valve may be secured.

With the foregoing and other objects in view, which will appear as the description proceeds, the invention resides in the construction hereinafter described and claimed, it being understood that changes may be made in the precise embodiment herein disclosed without departing from the spirit of the same.

45 In the accompanying drawings forming part of this specification:—

Figure 1 is a cross-sectional view through a fragment of a flushing tank and the valve.

Fig. 2 is a cross-sectional view through a 50 modification of the valve.

Referring now to the letters of reference placed upon the drawings:—

A, denotes a flushing tank, B, a valve seat, C, indicates a valve constructed of cork or other buoyant material, or it may be a hollow metallic ball. D, is the usual valve stem secured to the valve in any suitable manner, and E, indicates a rubber cup or sleeve adapted to cover the valve, or that portion of the valve which would ordinarily be in contact with the valve seat when closed.

The rubber cup is constructed of sufficiently elastic material that it may be readily expanded to receive the valve proper, and so also the wall of said cup is sufficiently thick to insure a proper seating of the valve at all times.

By employing my device in connection with a valve constructed of cork or other buoyant material there is no danger of the valve being "water-logged" through leakage or other cause, and a proper seating of the valve is assured, due to its yieldable outer surface.

Having thus described my invention, what I claim is:

1. In a device of the character described, a valve having an approximately hemispherical shape, and an inclosing elastic cup conforming to the curved surface of the valve and with an inwardly directed flange overlapping the plane surface of the latter, whereby it may be secured to the valve against accidental dislodgment.

2. In a device of the character described, a valve having an approximately hemispherical shape, and an inclosing rubber cap conforming to the curved surface of the valve and provided with an inwardly directed flange overlapping the outer edge of the plane surface of said valve.

In testimony whereof, I sign this specification in the presence of two witnesses.

WILLIAM MOUAT.

Witnesses:
